UNITED STATES PATENT OFFICE

RAYMOND C. AGNER, OF BURLINGTON, WISCONSIN

ANTENNA FOR RADIO SYSTEMS

Application filed May 16, 1927. Serial No. 191,726.

This invention relates to antennæ for radio systems.

Objects of this invention are to provide a novel form of radio antenna which is particularly adapted for radio receiving sets and which is so constructed that a great length of wire is employed, although located in a relatively restricted space, so that the extended or elongated wires usually employed are not necessary, and in which the chance of a broken or sagging wire is reduced to a minimum, and in which the chances of a poor or faulty connection or of grounds or undesirable connections to the wire are wholly avoided.

Further objects are to provide a novel form of antenna which is non-directional, although constructed primarily of wire, which presents a large surface to the radio waves, and which is remarkably free from static or interference of this general type, but which, instead, materially promotes the clarity of reception.

Further objects are to provide an antenna which is very simple to construct, which is of attractive appearance, and which may be readily installed.

Embodiments of the invention are shown in the accompanying drawings in which:

30 Figure 1 is a view of one form of the antenna;

Figure 2 is a top plan view of the structure shown in Figure 1;

Figure 3 is a view of a modified form of 35 antenna;

Figure 4 is a sectional view of the tip portion of the antenna shown in Figure 1;

Figure 5 is a view of the tip portion showing a modified form;

40 Figure 6 is a detail of the base portion of the antenna.

Referring to the form shown in Figures 1, 2, and 4, it will be seen that the antenna comprises an upper and a lower spider indicated generally by the reference characters

1 and 2. These spiders are of identical construction and are each provided with outwardly projecting parallel arms radiating from a central hub 3 and terminating in apertured arrow heads or points 4. These arrow heads are provided with notches 5 on opposite sides and are preferably apertured to reduce the weight. The upper spider 1, as may be seen from Figure 4, is screwed upon the upper end of a central pipe or standard 6. The standard also carries at its upper end an insulating washer or bushing 7 upon which the central pointed tip 8 is screwed, as may be seen from Figure 4. This tip is provided with a screw 9 in its interior portion, which receives a ground wire 10, such ground wire extending downwardly through the entire device, and providing an efficient means for carrying off static. The tip, it will be seen, is insulated entirely from the rest of the antenna system and is securely grounded.

The lower spider 2 is screwed upon the lower end of the standard 6, as shown in Figure 6, and the lower end of the standard projects below the spider 2 and is screwed into an insulating bushing 11, which may be relatively heavy, as indicated. This bushing is externally threaded and screws into a connecting fitting or nipple member 12 which is provided with outwardly projecting apertured ears 13 (see Figure 6) for the reception of guy wires, as indicated in Figure 1. The lower end of the fitting 12 is screwed into the supporting pipe or lower upright 15 which in turn is screwed into a base 16 provided with a flange apertured for the reception of the attaching lag screws or bolts 17, as shown in Figures 1 and 6.

A continuous wire 18 is looped back and forth over the arrow heads 4 of the upper and lower spiders 1 and 2, as shown in Figures 1 and 2, and its ends are clamped beneath the head of a bolt 19 secured to the lower spider 2. This bolt projects through

the lower spider and is provided with nuts 20 for clamping the lead-in wire 21 in place.

It is preferable to construct the spiders 1 and 2 of aluminum stampings or castings, or 5 else of copper plated malleable iron. The wire is preferably formed of copper and may be stranded, if desired.

In the form shown in Figure 5, substantially the same construction is followed with 10 the exception that the upper spider 22 is provided with a central aperture 23, and an insulating disc 24 is secured in place by means of rivets or bolts, as indicated. In this case, the spiders are not connected to the 15 central pipe 15. This central pipe extends through the insulating disc 24 and is clamped thereto by means of a lower nut 25 and the upper tip or projecting portion 26. The tips 8 and 26 are preferably provided with hexagonal lower portions, as shown in Figures 20 1 and 5.

In the form shown in Figure 3, substantially the same construction is followed with 25 the exception that the upper and lower spiders 27 and 28 are each provided with cutout portions bridged by insulating discs 29. These insulating discs receive the central pipe 30 and preferably the lower portion of the pipe is provided with a closure cap 31 and 30 the upper portion joined in a suitable manner, as by means of the nipple 32 and elbow 33 with a laterally projecting bracket or pipe 34. This lateral pipe or horizontal portion is screwed into a flanged fitting 35. This 35 flanged fitting is bolted to the side wall 36 of the house.

In each case, it may be found desirable to ground the supporting pipes. In the forms shown in Figures 3 and 5, the central standard 10 is not connected to the antenna system, but is connected to the main support. In the form shown in Figures 1, 2, 4, and 6, the central standard 6 is electrically connected to the antenna portion, and is insulated from 45 the supporting pipe.

It will thus be seen that a novel form of antenna has been provided which presents a large surface to the incoming radio waves and which employs a relatively long length 50 of wire and maintains this wire in a compact formation free from any possibility of sagging portions or loose joints.

It will be seen further that the antenna portion will be tuned by the tuning instrumentality of the set to the incoming waves while the other portions of the device will be grounded and insulated from the antenna and untuned to the incoming waves.

This grounded portion will thus serve as a 60 means for carrying off static disturbances and inasmuch as it is located in close proximity to the antenna itself, it is obvious that it will relieve the antenna of a large portion of the static ordinarily present in radio reception.

Although the invention has been described

in considerable detail, such description is intended as illustrative rather than limiting as the invention may be variously embodied and as the scope of such invention is to be determined as claimed.

70

I claim:

1. A radio antenna comprising a pair of spaced metal spiders, a support for holding said spiders, said support being insulated from said spiders, each of said spiders having radially projecting arms provided with arrow heads at their ends, and a continuous wire looped back and forth between the spiders and electrically joined to the arrow head ends of the arms.

75

2. A radio antenna comprising a pair of spaced metal spiders, a support for holding said spiders, said support being insulated from said spiders, each of said spiders having radially projecting arms provided with arrow heads at their ends, and a continuous wire looped back and forth between the spiders and electrically joined to the arrow head ends of the arms, said antenna having a grounded tip insulated from said spiders and located above the uppermost spider, said tip being pointed.

80

3. A radio antenna comprising a pair of spaced metal spiders arranged horizontally and located one above the other, said spiders having projecting arms, a conducting wire looped back and forth over the arms of the spiders and electrically connected to said spiders, said arms being arranged in spaced relation, a lead-in wire clamped to the lower of said spiders, a central standard passing through the said spiders, a supporting pipe insulated from said spiders and extending downwardly below the lower of said spiders.

85

4. A radio antenna comprising a pair of spaced spiders arranged horizontally and located one above the other, said spiders having projecting arms, a conducting wire looped back and forth over the arms of the spiders, said arms being arranged in spaced relation, a lead-in wire clamped to the lower of said spiders, a central standard passing through the said spiders, a supporting pipe insulated from said spiders and extending downwardly below the lower of said spiders, a pointed upper tip carried by said central standard and insulated from said spiders, a ground wire connected to said tip and leading downwardly through the said central standard.

90

5. A radio antenna comprising a pair of vertically spaced horizontally arranged metal spiders provided with radiating arms terminating in arrow heads, said arrow heads being provided with notches therein, a conducting wire looped back and forth over the arrow heads and seated within the said notches and electrically connected to said arrowheads, a lead-in wire clamped to the lower spider, a central standard of tubular construction electrically connected to said spi-

ders, a projecting pointed cap carried by the upper end of said standard and insulated therefrom, a tubular support insulated from said spiders and from said standard, and a ground wire leading upwardly through said 5 tubular support and said standard and connected to said tip.

In testimony that I claim the foregoing I have hereunto set my hand at Burlington, in the county of Racine and State of Wisconsin.
